CLAIM

The ornamental design for a loudspeaker magnet housing, as shown and described.

DESCRIPTION

FIG. 1 is a top plan view of a loudspeaker magnet housing showing my new design, with the broken line structure forming no part of the claimed design and being for illustrative purposes only;

FIG. 2 is a side elevational view thereof; and

FIG. 3 is a top and side perspective view.

The rear of the housing is conventional.

FIG. 1.

FIG. 2.

FIG. 3.
